[57] CLAIM

The ornamental design for a combined arm and holder used in apparel manufacture to transfer fabric items between work stations, as shown and described.

DESCRIPTION

FIG. 1 is a top perspective view of a device used in apparel manufacture to transfer fabric items between work stations, showing our new design;

FIG. 2 is a front elevational view thereof;

FIG. 3 is a rear elevational view thereof;

FIG. 4 is a top plan view thereof;

FIG. 5 is a right side elevational view thereof, taken in the direction of arrows 5—5 in FIG. 1; and,

FIG. 6 is a left side elevational view thereof.
